Des. 234,903
Patented Apr. 15, 1975

234,903

WIRE OR ROPE TIGHTENER

Albert T. Berg, Jr., and Howard Langlie, both of
Ellendale, Minn. 56026

Filed Sept. 27, 1973, Ser. No. 401,347

Term of patent 14 years

Int. Cl. D8—05

U.S. Cl. D8—44

Fig. 1

Fig. 2

Fig. 3

Fig. 4

Fig. 5

Fig. 6

FIG. 1 is a perspective view of a wire or rope tightener embodying our new design;

FIG. 2 is a top plan view thereof;

FIG. 3 is a front elevational view of our design;

FIG. 4 is a rear elevational view thereof;

FIG. 5 is a side view taken from the right in FIG. 2, and

FIG. 6 is a side view taken from the left in FIG. 2.

We claim:

The design for a wire or rope tightener, substantially as shown.
